UNITED STATES PATENT OFFICE.

EDWARD F.-G. GIBBS, OF WASHINGTON, DISTRICT OF COLUMBIA.

TOOL-POST-BORING-BAR HOLDER.

1,308,281.

Specification of Letters Patent.

Patented July 1, 1919.

Application filed October 15, 1915. Serial No. 55,999.

To all whom it may concern:

Be it known that I, EDWARD F.-G. GIBBS, a citizen of the United States, residing at Washington, in the District of Columbia, have invented certain new and useful Improvements in Tool-Post-Boring-Bar Holders, of which the following is a specification.

My invention relates to improvements in that class of boring bar holders which are held in the tool posts of common engine lathes, and which hold, in turn, boring bars, which bars hold in turn inserted cutters, or the tools used for boring metals. It is hereinafter fully described, shown in the accompanying drawing; and then specifically defined in the appended claims.

The specific objects of this invention are to obtain a one-piece holder, of the character described; which allows the supporting tool post wedge to come as near the strain receiving cutter point as possible; which brings the said cutter point directly in front of the said tool post wedge; carries a long open-ended barrel, the hollow of which constitutes a horizontally elongated, bar-holding aperture, whose apex is turned toward the tool post; is adapted to receive boring bars of various diameters and support them in bearings of three contact points each, at each end of the said aperture; and to obtain a holder which can be economically made.

I obtain these objects by means of the mechanism illustrated in the accompanying drawing, which forms a part of this specification, and in which drawing—

Figure 1 is a plan view of the holder held in a tool post of the usual type and holding a bar in working position.

Fig. 2 is a front end elevation, showing a section of the bar on line $z-z$ of Fig. 1.

Fig. 3 is a side elevation; and

Fig. 4 is a section of the barrel only, on line $\alpha-\alpha$, of Fig. 2.

Reference now being had to the details of the drawing by letters, in which similar letters refer to similar parts throughout the several views—

A designates the stock, or shank, a straight bar of rectangular cross-sectional figure by which the holder is held in the tool post; α designates the neck which connects the stock and barrel referred to later; and α^2 the very acute angular opening which separates the stock and barrel from their rear ends to the neck.

B designates the open barrel; b designates the bar-holding aperture; b^2 the chambered recess, and b^3 the set screw lugs.

C designates the set screws which hold the bar in the aperture;

D designates the boring bar;

E designates the inserted cutter or tool;

O designates the tool post;

P designates the tool post wedge and p its width dimension lines projected;

Q designates the tool post ring.

It is to be seen that the stock, A, and bar-holding member, or barrel, B, integral in this case, are parallelly disposed indirectly connected at their front ends, which ends coincide, by the intervening neck α , all of which, stock, neck and barrel begin on a line or plane perpendicularly to the axis of the bar-holding aperture, but they are separated from their rear ends to the neck by the acute slightly angular opening α^2 .

This opening allows the stock to pass through the tool post, O, until its front end comes back to the front end of the tool post wedge, P, upon which it bears. This construction brings the bearing as near the point of the strain receiving cutter E, as possible.

There are three objects in view in making the opening α^2 slightly angular; the wedge, P, being parallel to the stock, A, and the bar, D, parallel to the barrel B, the acuteness of the angularity of the opening, α^2 , throws the strain-receiving point of the cutter E, immediately in front of the wedge to its maximum extent as shown by the projected lines, p ; it makes a wide opening at the rear end of the barrel and shortens the neck, α . It is to be noted that the holder body, or the whole integral subject of my construction is a one-piece tool.

From Fig. 2 it is to be seen that the bar-holding aperture b of the barrel is elongated horizontally instead of vertically. This enables the operator to increase the size of the bar as the size of the hole he is boring increases, without lowering the elevation of the holder.

It is further to be seen from Fig. 2 that the apex of the aperture or bar seat is turned toward the stock, while the set-screws, C, enter through lugs b^3 from the opposite side and force the bar as near the tool post as possible, thus insuring greater rigidity.

It is also to be seen from all the figures,

especially Fig. 2, that the bar's bearings consist of three contact points of triangular position at each end of the aperture, one of which is the set screw forcing the bar 5 against opposite walls in the aperture.

And it is further to be noted that the bar bears at the ends of the aperture rather than in the center because of the chambered recess, b^2 , shown in Figs. 2 and 4.

10 Rigidity, the most important element in a boring tool is augmented by each of several features of the holder which coöperate to that end; as follows;—the forward position of the neck, and the deep opening between 15 the stock and the barrel, which makes the minimum distance from strain to resistance, or from the cutter-point to the tool post wedge bearing, possible; the long distance between the bar-bearings in the barrel; the 20 slightly angular character of the said opening; the solid character of the one-piece holder; and the direction of the apex of the bar aperture toward the stock.

The construction of this one-piece holder 25 also makes for economy in manufacture.

Having thus fully described my invention, I desire to secure by Letters Patent what is new according to the following claims:

1. As an article of manufacture, a one- 30 piece tool-post boring-bar holder body; comprising a stock; and a barrel beginning on a common plane, indirectly; connected at their front ends by an intervening neck integral with both; and having a slightly 35 angular opening between the said stock and barrel from the said neck to the rear end of the barrel; all substantially as set forth.

2. A tool post boring bar holder; comprising a stock; and a barrel; connected at their 40 front ends by a neck integral with both, all

of which, stock, neck and barrel begin on a line perpendicular to the axis of a bar-holding aperture through the said barrel; and having a slightly angular opening between the said stock and barrel from the 45 said neck to the rear end of the barrel; and means for holding a boring bar rigidly in the said aperture; all substantially as set forth.

3. A tool post boring bar holder, comprising a stock; and a barrel; connected at their front ends by a neck integral with both, all of which, stock, neck and barrel begin on a line perpendicular to the axis of a bar holding aperture through the said barrel; 50 and having a deep slightly angular opening between the said stock and barrel from the said neck to the rear end of the barrel; and a set screw near each end of the said barrel for holding a boring bar rigidly in the said 55 aperture; all substantially as set forth.

4. A tool post boring bar holder, comprising a stock; and a bar-holding member; indirectly connected at their front ends by an intervening neck integral with both, all 60 of which stock, neck and member begin on a line perpendicular to the bar seat of the said member; and having a deep slightly angular opening between the said stock and member from the neck to the rear end of 65 the said member; and means for holding a boring bar in the said bar seat, by forcing it in a horizontal direction, and toward the said stock; all substantially as set forth.

In testimony whereof I affix my signature 70 in presence of two witnesses.

EDWARD F-G. GIBBS.
